(57) **CLAIM**

The ornamental design for a LED book light, as shown and described.

DESCRIPTION

FIG. 1 is a front view of a LED book light, showing my new design.

FIG. 2 is a rear view of the LED book light.

FIG. 3 is a right side view of the LED book light.

FIG. 4 is a left side view of the LED book light.

FIG. 5 is a top view of the LED book light.

FIG. 6 is a bottom view of the LED book light.

FIG. 7 is a front perspective view of the LED book light.

FIG. 8 is a rear perspective view of the LED book light.

FIG. 9 is an enlarged view of the FIG. 1.

FIG. 10 is an enlarged view of the FIG. 2.

FIG. 11 is an enlarged view of the FIG. 4; and,

FIG. 12 is an enlarged view of the FIG. 1.

The broken line shown in the drawings define the boundary of the enlarged views and form no part of the claimed design.
